UNITED STATES PATENT OFFICE

LOUIS JANOF, OF WASHINGTON, DISTRICT OF COLUMBIA

DESIGN FOR A HAND BAG

Application filed February 12, 1932. Serial No. 42,825. Term of patent 3½ years.

To all whom it may concern:

Be it known that I, LOUIS JANOF, a citizen of the United States, residing at the District of Columbia, in the city of Washington, have invented a new, original, and ornamental Design for Handbags, of which the following is a specification, reference being had to the accompanying drawings, forming part thereof.

Fig. I is a front view showing my new design in open position.

Fig. II is a side view showing my new design in open position.

Fig. III is a front view of my new design in closed position.

I claim:

The ornamental design for a handbag, as shown.

LOUIS JANOF.
